[57] ABSTRACT

A precious metal ear-ornament clip whose "grip" on the ear lobe is adjustable and is maintained by maintenance of the angular relationship of its two constituent clip members. Said maintenance is ensured by the frictional engagement of the inwardly directed surfaces of two limbs (which form a part of one clip member and whose free ends are pivotally connected to the other clip member) with the outwardly directed surfaces of two further limbs (carried by the other clip member) which are forced apart by a spring located between them. The spring is essential because the precious metal or precious metal(s) alloys may lack the requisite spring properties.

EAR-ORNAMENT CLIPS

This invention relates to ear-ornament clips.

According to Webster's International Dictionary, one of the meanings of the word "carat" is a twenty-fourth part and the word is used in expressing the proportionate fineness of a gold alloy (for example, a gold alloy containing fourteen twenty-fourths by weight of gold is fourteen carats fine). As employed herein, the term "proportionate fineness" is to be taken as applying to both silver and platinum, mutatis mutandis, besides applying to gold since it is well-known that in the jewellery field copper is added to silver (silver 92½ percent copper 7½ percent composition by weight for sterling silver) to strengthen and to harden the pure metal whose strength and hardness are not of the requisite order, each of copper and iridium is added to platinum and an alloy is used which consists of 50 percent palladium and 50 percent silver.

In U.S. Pat. No. 3,237,266, I have disclosed an ear-ornament clip comprising a first clip member adapted to be pressed against one side of the lobe of an ear, a second clip member in the form of an arm pivoted at one end to the first clip member by interengaging pivotally connected parts of the two members, said arm at its other and free end being adapted to be pressed against the other side of the ear lobe, means to maintain the two clip members frictionally in the ear lobe engaging relationship and comprising, as part of one of said clip members, a bifurcation comprising part of the pivotal connection of the two clip members, and, provided as part of the other clip member, resilient parts adapted to mate frictionally between the limbs of said bifurcation and separated from the pivot axis of said pivotal connection of the two clip members.

The principal object of the present invention is to provide an ear-ornament clip which functions as efficiently as those sold under said patent even when made of one of the precious metals or of an alloy containing one or more of the precious metals whose proportionate fineness may be such as to inhibit the necessary springiness of the parts which participate in said frictional mating.

It is a subsidiary object of the present invention to be able to continue to sell the ear-ornament clip construction which has become widely known by sale and advertising with as little structural modification as is humanly possible whilst achieving the principal object of the present invention.

It is a further subsidiary object of the present invention to provide an ear-ornament clip with a concealed custom-made spring device whose scale decreases with that of the clip itself and which is fitted to the clip in a simple but effective manner.

It is yet a further subsidiary object of the present invention to provide an ear-ornament clip in which there is a positively located spring which the wearer of the clip is unable to avoid loading whenever the clip is temporarily secured to an ear lobe, said loading being the cause of the established "grip" on the lobe being maintained by frictional mating of the constituent members of the clip. Said spring may consist of an element made wholly of a natural or synthetic elastomeric material, the sizes and shapes in relation to one another of the said element as manufactured on the one hand and the spaced to be occupied thereby in the clip as manufactured on the other hand being such as to ensure that said element, when properly positioned in said clip would always be under compression and would thus be adapted to maintain said frictional mating. However, said spring may alternatively consist of a substantially V-shaped element made of spring metal whose limbs would, when the V-shaped element has been properly positioned in said clip, always be under compression and would thus be adapted to maintain said frictional mating.

The present invention will now be more particularly described with reference to the accompanying drawings, in which:

FIG. 1 illustrates a side elevation of first and second clip members, in assembled condition, of an ear-ornament clip made of one of the precious metals and constructed according to the present invention, one free end of that clip member to which it is intended to fix the ornament concerned being

broken away and sectioned to reveal the eyelet for the mounting of said ornament or for the mounting of the support to which the ornament may be fixed;

FIG. 2 illustrates a top plan view looking in the direction of the arrow A in FIG. 1 of only that clip member to which it is intended to fix said ornament, said top plan view illustrating clearly the conformation in one embodiment of said clip of the resilient parts carried by said clip member as manufactured and before the fitting thereto of said compression spring means;

FIGS. 3 and 4 illustrate a side elevation and a top plan view, respectively, of the compression spring means adapted for use in said one embodiment of said clip;

FIG. 5 is a view similar to that of FIG. 2 except that the conformation (in an alternative embodiment of said clip) is illustrated of the resilient parts carried by said clip member as manufactured and before the fitting thereto of said compression spring means;

FIGS. 6 and 7 illustrate a side elevation and a top plan view, respectively, of the compression spring means adapted for use in said alternative embodiment of said clip; and

FIGS. 8 and 9 illustrate top plan views of said one and said alternative ear-ornament clips each fitted with the respective one of the compression spring means.

Referring to FIGS. 1, 8 and 9, there is illustrated therein an ear-ornament clip part or which includes a first clip member 1 and a second clip member 2, the members 1 and 2 being referred to by those in the jewellery trade in at least certain regions of the world as the back section and the front section, respectively. The member 1 consists of an arm 3 which is shaped in order to be pressed (when in use) with comfort against the inside surface of the lobe of the ear and which connects two parallel limbs 4, 5 in the vicinities of the free ends of which depressions 6 (only one of which is visible) are so formed by a pressing operation as to result in the provision of pips or protuberances (not visible in the drawings) which extend towards one another and which are axially aligned with one another. The parallel limbs constitute a pair of bifurcated arms which are a part of said first clip member 1.

The member 2 (see also FIGS. 2 and 5) is appropriately shaped and formed to provide two parallel lugs 7 and two arcuate elongated limbs or bifurcated arms 8 (only one of said lugs and one of said arcuate elongated limbs being visible in FIG. 1), said lugs 7 being spaced from said limbs 8. Holes (not illustrated) are punched in said lugs 7 for the accommodation of the pips or protuberances on the limbs 4, 5, said holes on the one hand and said pips or protuberances on the other hand constituting the pivotal connection of said members 1, 2 to one another. Said limbs 8 are subjected to a pressing operation which results in the formation of arcuate depressions 9 in the outwardly directed surfaces thereof and corresponding protuberances 10 which interrupt the inwardly directed surfaces thereof and which are in axial alignment with and extend towards one another.

That end of the member 2 which is remote from the lugs 7 and the limbs 8 is appropriately shaped and formed to provide an eyelet which is indicated in general by the reference numeral 11, said eyelet being to facilitate the fixing or mounting of the ornament concerned or for the mounting of the support to which the ornament may be fixed.

Having described the respects in which the members 1, 2 are identical in the two embodiments illustrated in the drawings, reference will now be made to FIG. 2 in which the arcuate elongated limbs 8 are not parallel as shaped and formed and to FIG. 5 in which the arcuate limbs 8 are parallel or substantially parallel as shaped and formed.

In FIG. 2 the limbs 8 are divergent in the direction of the eyelet 11 and the inwardly directed surfaces of said limbs (ignoring the protuberances 10 which interrupt said surfaces) are located in planes B which contain an angle of 12°.

In FIG. 5 the limbs 8 are parallel to one another or substantially so, this being the case because of the different type of compression spring means which is to be used and which will hereinafter be described.

Referring to FIGS. 3 and 4, there is illustrated therein an element 12 which is made of natural or synthetic elastomeric material (for example natural rubber) and which is arcuate in side elevation and substantially frusto-conical in top plan view. The radii of curvature adopted to impart the arcuate configuration are equal to or substantially equal to those adopted for the limbs 8. The element 12 has two flanks whose surfaces 13 are located in planes C which contain an angle of 14° and the end 14 of the element is rounded (see FIG. 4) to match the radius of curvature of the inside surface 15 of the junction 16 of the limbs 8. Moreover, the surfaces 13 have moulded therein, at the time when the elastomeric material is being cured, two aligned arcuate recesses 17 whose dimensions match as closely as possible those of the protuberance 10.

Referring now to FIG. 8, the element 12 is illustrated in position between the limbs 8, the protuberances 10 on said limbs extending into the recesses 17 formed in the surfaces 13 of said element, whereby mechanical inter-engagement is created between the element 12 which constitutes the compression spring means in this particular embodiment of the invention.

Referring to FIGS. 6 and 7, there is illustrated a substantially V-shaped element 18 made of springy metal (for example spring steel or beryllium copper), said element being arcuate in side elevation. The limbs 19 of the element 18 are subjected to a pressing operation which (as with the limbs 8 of the clip member 2) results in the formation of arcuate depressions 20 in the outwardly directed surfaces thereof and corresponding protuberances 21 which interrupt the inwardly directed surfaces thereof and which are in axial alignment with and extend towards one another. The limbs 19 are divergent and the inwardly directed surfaces thereof (ignoring the protuberances 21 which interrupt said surfaces) are located in planes D which contain an angle of 20°.

Referring now to FIG. 9, the element 18 is placed between the parallel limbs 8 (see FIG. 5) with the result that not only are the free ends of the limbs 19 forced closer together by or under the influence of the limbs 8 but also the free ends of said limbs 8 are forced farther apart by or under the influence of the element 18. The resultant appearance, in a top plan view, of this particular embodiment of the complete ear-ornament clip (namely, the two pivotally connected clip members 1, 2 and the spring means 18) is identical with or closely resembles that of the other embodiment of the complete ear-ornament clip which consists of the two pivotally connected clip members 1, 2 and the spring means 12, mutatis mutandis.

It should be noted from FIG. 8 that there is a space or clearance S between the round end 14 of the element 12 and the inner surface of the curved junction of the limbs 8. A similar clearance S exists between the outer surface of the bend in the element 18 and the inner surface of the curved junction of the limbs 19 (FIG. 9). These clearances must exist when the elements concerned have been inserted between the limbs concerned and should fall within the range from 0.004 to 0.007 inch. When the ear-ornament clip is being worn, the

spring element concerned will have become loaded and some of this clearance S will have been taken up.

It is not considered that the angles of 12°, 14° and 20° and the parallelism of the limbs 8 in FIG. 5 are of an importance 5 which is critical in the sense that an ear-ornament clip constructed in accordance with FIGS. 1, 2, 3, 4 and 8 will not work without the angles 12° and 14° specifically mentioned or in the sense that an ear-ornament clip constructed in accordance with FIGS. 1, 5, 6, 7 and 9 will not work without the 10 angle 20° and the parallelism of the limbs 8 specifically mentioned. The choice of the particular angles may be varied within limits which are in fact imposed by the decorative nature of the article itself (namely, the clip which is made of a precious metal or of an alloy which includes at least one precious metal) and by the desired overall dimensions of the article. The limbs 8 (which constitute the resilient parts of the other clip member 2) must not be caused by the elements 12, 18 to be so widely splayed or divergent in the direction of the eyelet 11 as to make very difficult such pivotal movement of 15 the clip member 1 relative to the clip member 2 as is necessary to cause the ear-lobe to be gripped. Conversely, the splaying or divergence must not be so little that the degree of compression of the elements 12, 18 is too small to maintain said frictional mating.

25 It will be obvious that the element 12 could be moulded so as to have protuberances thereon instead of and in the same positions as the recesses 17, provided that the limbs 8 were provided with recesses instead of and in the same positions as the protuberances 10 thereon. Similar remarks apply to the 30 limbs 8 and the spring element 18.

What I claim as my invention and desire to secure by Letters Patent of the United States is:

1. An ear-ornament clip comprising a first elongate clip part 35 having two bifurcated arms at one end thereof and an ear-engaging surface at the other end thereof, said first clip part further including first pivot-forming means on said bifurcated arms, said clip further comprising a second elongate clip part made of material including a precious metal, said second clip part including second pivot-forming means at a location intermediate its ends, said second pivot-forming means being adapted to coact with said first pivot-forming means to effect 40 pivotal connection of said clip parts, said second clip part further including, along the length thereof on one side of said second pivot-forming means, a pair of arcuate bifurcated arms 45 adapted to pass between said first-named bifurcated arms at one relative angular position of said pivotally interconnected first and second clip members, said second-named bifurcated arms forming a continuous inner surface therebetween, and elastic means disposed between said second-named bifurcated arms 50 stressing them apart and into frictional engagement with said first-named bifurcated arms when said clip parts are at said one relative angular position, said elastic means having an arcuate configuration substantially identical to that of said second-named bifurcated arms and in contact with said inner surface along substantially the entire length of said inner surface.
